UNITED STATES PATENT OFFICE.

CHRISTIAN W. HINRICHES, OF ST. LOUIS, MISSOURI.

REFRIGERATOR SHOW-CASE.

1,356,283.

Specification of Letters Patent. Patented Oct. 19, 1920.

Application filed March 24, 1917. Serial No. 157,161.

To all whom it may concern:

Be it known that I, CHRISTIAN W. HINRICHES, a citizen of the United States of America, and a resident of the city of St. Louis and State of Missouri, have invented 5 certain new and useful Improvements in Refrigerator Show-Cases, of which the following is a specification.

The primary object of this invention is to 10 provide an improved arrangement of parts in a refrigerator show case so that a continuous cycle of air will be given to the food-stuff chambers of the show case from the ice container through the food-stuff chambers 15 and returned to the ice container, from which the returned air will continuously pass through the ice container and food-stuff chambers.

Another object of this invention is to 20 provide a refrigerator show case with longitudinally arranged guideways, as well as a longitudinally arranged ice container so that the circulated air currents will be uniform in their cycling travel, thereby preventing 25 pocketing and stagnating the air.

Other and further objects will appear in 30 the specification and be specifically pointed out in the appended claims, reference being had to the accompanying drawings exemplifying the invention, and in which,

Figure 1 is a plan view of this improved 35 refrigerator show case.

Fig. 2 is a front elevation, partly in section, taken on the line II—II of Fig. 1.

Fig. 3 is a vertical section taken on the 40 line III—III of Fig. 1.

Fig. 4 is a fragmentary horizontal section taken on the line IV—IV of Fig. 3.

Referring to the drawings, this improved 45 refrigerator show case comprises a front show glass 1, bottom 2, rear wall 3 and top wall 4, said top wall 4 comprising a plurality of glass swinging doors 5, which provide access to the upper food-stuff chamber 6, and ice container covers 7 and 8 that provide access to the ice container 9.

Formed in the rear wall 3 are a plurality 50 of swinging doors 10 which provide access to the lower food-stuff chamber 11. As shown more clearly in Figs. 3 and 4, the ice container 9 is located adjacent the rear wall 3 in the upper chamber 6, and extends longitudinally therein so that said ice container is approximately the length of said chamber 6. The ice container 9 comprises a front side wall 12 which is perforated, a rear wall

which is composed of a perforated strip 13 which depends downwardly from the top wall 4, and a solid portion 14.

An inclined drip pan 15 is arranged beneath the bottom 16 of the ice container. Dividing the upper chamber 6 from the lower chamber 11 is a horizontally and longitudinally arranged cold air deflector board 17, said deflector board also serving as a shelf for the food-stuffs in said upper chamber 6.

This deflector board 17 is supported at its ends by the end walls 18 of the show case, and it is to be noted that the front edge 19 of said deflector board is arranged at a distance away from the show glass 1, thereby forming a longitudinal passageway 20 which extends the full length of the show case.

Located between the solid portion 14 of the rear wall of the ice container and the rear wall 3 of the show case, is a vertically and longitudinally arranged passageway 21 which leads to the rear perforated portion 13.

In getting this improved refrigerator show case ready for operation, the ice container 9 is filled preferably with cracked ice, so that when said ice is lying in mass formation in the container, which is preferably kept filled, the ice will be in a porous condition, so that the air can circulate therethrough, and inasmuch as the cold air descends, the air contained in the ice container will fall to the bottom thereof and toward the front perforated wall 12, and out of the lowermost perforations in said wall, over the longitudinally arranged baffle strip 22, thereby passing over and around the food-stuffs mounted on the deflector board 95 or shelf 17, toward and through the longitudinally arranged passageway 20, into the lower food-stuff chamber 11, and over and around the provisions arranged in the bottom 2, and as the temperature of the cold air 100 of the chamber 11 arises as the air travels toward the rear of said chamber 11, said warmer air will ascend, and upon engaging the inclined bottom of the drip pan 15, said warm air will be deflected toward and up 105 the vertical passageway 21 toward the perforated strip 13, and upon engaging the inclined deflector board 23, will be forced through the perforations of said perforated strip 13 and into the top of the ice container, 110 said warm air after being introduced into said ice container upon becoming chilled

will descend and be discharged through the perforations of the front wall 12 as afore related.

It is therefore seen that on account of the 5 perforations of the front wall 12 of the container extending to a lower plane than the perforations of the rear strip 13, that the cold air will always pass through said perforated wall 12, over the shelf 17, and to- 10 ward and down the passageway 20, and after the cold air has entered the lower chamber 11, said air will be forced toward the rear of the show case on account of the down draft, through said passageway 20, at 15 which point said cold air will tend to be- come warmer, thereby arising and being de- flected toward the vertical passageway 21, on account of engagement with the inclined bottom of the drip pan 15 which is inclined 20 upwardly toward said passageway 21. Fur- thermore, the ice container being longitudi- nally arranged and extending the full length of the show case, and the passageways 20 and 21 being of the same length, there will 25 be a uniform current of air traveling and making a complete cycle through the front wall 12 of the ice container over the full length of the shelf 17 and incidentally over the full length of the bottom 2, in which all 30 of the air contained in the upper and lower chambers will be forced to continually flow or travel, thereby eliminating the pocketing of any air bodies, in which the continual flowing cold air passing over the food-stuffs 35 of the upper and lower chambers will keep said foodstuffs fresh and in a salable con- dition.

In an improved refrigerator show case of this character on account of the front wall 40 being transparent as well as the top wall being provided with the glass doors 5, the clerk behind the show case when waiting on

a customer can readily follow the indicating directions of a customer through the glass doors as the customer indicates or points 45 against the transparent front wall.

What I claim is:

1. A refrigerator show case having trans- parent front and top walls, a horizontally arranged shelf having a solid surface di- 50 viding said case into a pair of chambers ar- ranged one above another, an ice container having openings formed in opposing walls thereof located to the rear of the upper chamber, a passageway formed adjacent the 55 front wall of said shelf leading from the upper to the lower chamber, and a second passageway oppositely disposed from said first mentioned passageway leading from said lower chamber to said ice container. 60

2. A refrigerator show case having a transparent front wall, a pair of chambers, a horizontally arranged solid surface shelf dividing said chambers, an ice container having openings formed in opposing walls 65 thereof located in the upper one of said chambers adjacent the rear wall thereof, the openings of one of said walls located on a plane lower than the openings of said other wall of said container, a passageway lead- 70 ing from said upper chamber to the lower chamber located adjacent the front wall of the show case, and a second passageway op- positely disposed from said first mentioned passageway leading from said lower cham- 75 ber to the side of said ice container, in which the openings are arranged on a higher plane above the openings of said other wall of said ice container, said shelf providing means for deflecting air currents from said 80 container to said first mentioned passage- way.

CHRISTIAN W. HINRICHES.
